US0D1060428S

(12) **United States Design Patent** (10) Patent No.: **US D1,060,428 S**
(45) Date of Patent: ** *Feb. 4, 2025

(54) **PLAYBACK DEVICE**(71) Applicant: **Sonos, Inc.**, Santa Barbara, CA (US)(72) Inventors: **Roland Bird**, Eindhoven (NL); **Niels van Hoof**, Eindhoven (NL); **Roger Swales**, Eindhoven (NL); **Mieko Kusano**, Santa Barbara, CA (US); **Tadeo T. Toulis**, Santa Barbara, CA (US); **Maximillian Burton**, Santa Barbara, CA (US); **Stefan Reichert**, Santa Barbara, CA (US)(73) Assignee: **SONOS, INC.**, Goleta, CA (US)

(*) Notice: This patent is subject to a terminal disclaimer.

(**) Term: **15 Years**(21) Appl. No.: **29/801,178**(22) Filed: **Jul. 27, 2021**

(56)

CLAIM

The ornamental design for a playback device, as shown and described.

DESCRIPTION

FIG. 1 shows an isometric view of a first embodiment of a playback device on a first example environment.

FIG. 2 shows a top view of a first embodiment of a playback device on a first example environment.

FIG. 3 shows an isometric view of a first embodiment of a playback device on a second example environment.

FIG. 4 shows a side view of a first embodiment of a playback device on a second example environment.

FIG. 5 shows side view of a second embodiment of a playback device on a third example environment.

FIG. 6 shows an isometric view of a second embodiment of a playback device on a third example environment.

FIG. 7 shows a front view of a third embodiment of a playback device on a fourth example environment.

FIG. 8 shows an isometric view of a third embodiment of a playback device on a fourth example environment.

FIG. 9 shows a front view of a third embodiment of a playback device on a fifth example environment.

FIG. 10 shows an isometric view of a third embodiment of a playback device on a second example environment.

FIG. 11 shows an isometric view of a third embodiment of a playback device on a first example environment.

FIG. 12 shows a top view of a third embodiment of a playback device on a first example environment.

FIG. 13 shows an isometric view of a third embodiment of a playback device on a second example environment.

FIG. 14 shows a side view of a third embodiment of a playback device on a second example environment.

FIG. 15 shows a side view of a fourth embodiment of a playback device on a third example environment.

FIG. 16 shows an isometric view of a fourth embodiment of a playback device on a third example environment.
FIG. 17 shows a front view of a fifth embodiment of a playback device on a fourth example environment.
FIG. 18 shows an isometric view of a fifth embodiment of a playback device on a fourth example environment.
FIG. 19 shows a front view of a fifth embodiment of a playback device on a fifth example environment.
FIG. 20 shows an isometric view of a fifth embodiment of a playback device on a fifth example environment.
FIG. 21 shows an isometric view of a fifth embodiment of a playback device on a first example environment.
FIG. 22 shows a top view of a fifth embodiment of a playback device on a first example environment.
FIG. 23 shows an isometric view of a fifth embodiment of a playback device on a second example environment.
FIG. 24 shows a side view of a fifth embodiment of a playback device on a second example environment.

FIG. 25 shows side view of a sixth embodiment of a playback device on a third example environment.
FIG. 26 shows an isometric view of a sixth embodiment of a playback device on a third example environment.
FIG. 27 shows an isometric view of a fourth embodiment of a playback device on a first example environment.
FIG. 28 shows a top view of a fourth embodiment of a playback device on a first example environment.
FIG. 29 shows a front view of a sixth embodiment of a playback device on a fourth example environment; and,
FIG. 30 shows an isometric view of a sixth embodiment of a playback device on a fourth example environment.
The features shown in broken lines form no part of the claimed design.
The dash dot dash broken lines define the boundaries of the claim, and forms no part thereof.
